UNITED STATES PATENT OFFICE.

ARTHUR B. FOSTER, OF WASHINGTON, DISTRICT OF COLUMBIA.

MANUFACTURE OF SULFURIC ACID.

1,277,896.

Specification of Letters Patent. Patented Sept. 3, 1918.

Application filed July 23, 1914. Serial No. 852,728.

To all whom it may concern:

Be it known that I, ARTHUR B. FOSTER, a citizen of the United States, residing at Washington, District of Columbia, have invented certain new and useful Improvements in the Manufacture of Sulfuric Acid, of which the following is a specification.

The present invention relates to improvements in the chamber process of making sulfuric acid, and in an apparatus therefor, and has for its particular object, the production of a method and an apparatus, whereby the amount of acid produced in a given chamber plant may be increased, and the amount of concentrated sulfuric acid produced in a given chamber plant, may also be increased. By this method also it is more easy to regulate the process, in order to make the same run smoothly.

These and other objects are obtained by the use of the apparatus shown in the annexed drawings, in which drawings, Figure 1 shows a vertical diagrammatic view of an acid plant, equipped in accordance with my invention, and Fig. 2 shows the location of one preferred form of atomizer.

In said drawings 1 represents a source of hot gases containing SO_2 , such as sulfur or pyrites burners, which may be of the usual and well known type, 2 represents a flue leading to a Glover tower 3, 4—4 represent the chambers, shown as being broken away, in order to get the entire drawing on one sheet, 5 represents the ordinary Gay Lussac tower, 6 represents an auxiliary Gay Lussac tower or regulating tower. The parts 3, 4, 5 and 6 are connected in the usual way with each other, by means of suitable flues 7, which may in the present instance consist of glazed terra cotta pipes. This much of the apparatus is all old and well known, and no claim is made thereto.

Placed within the flues 7, leading into the chambers 4, I place atomizers 8, which are fed with chamber acid, or other sulfuric acid, preferably acid containing oxides of nitrogen, in place of which I may employ if desired, waste acids from nitrating processes, which contain nitric acid, which may be more or less diluted. The acid delivered to the atomizers may be introduced through pipes 9, by means of centrifugal pumps or the like, as illustrated at 10.

After each of the chambers, or after some

of the chambers, I preferably provide towers 12, which may be Lunge plate towers, or other similarly operating devices, for the removal of mist and droplets of acid, from the gases. These towers may be omitted if desired, but will preferably be placed after 60 each of the chambers, except the last. These towers may be irrigated with acid, such as chamber acid, delivered through pipes 13, by means of pumps 14. At 15, I have shown a pump drawing acid from either the last 65 Lunge tower or the last chamber, or both, and delivering this acid to either the atomizer placed before the last chamber, or to the last Lunge tower, or to both, suitable valves being shown for this purpose. Connected to the bottom of the last chamber 4, and also connected to the bottom of the tower 6, I have shown a pipe, for introducing acid from the last part of the tower system, into an atomizer placed before the first 75 chamber, by means of a pump 10. This arrangement may also be extended, and all the acid used for the atomizers may be drawn from the last chamber, or partly from the last chamber, and partly from the Gay Lussac 80 tower or auxiliary tower, and passed into each of the several atomizers. The pipe 17 may be employed for delivering acid from the bottom of one of the chambers at the front part of the series, to the regulating 85 tower, or to the Gay Lussac tower, or if desired, the acid from the Glover tower, and acid from the first chamber may be mixed, and used for washing the gases in the Gay Lussac towers. 90

In operating the plant, I preferably introduce all the air to the pyrites burners, below the grates, in order that the gases produced in said burners will contain a relatively large amount of SO_2 , and a relatively 95 small amount of free oxygen, by means of which the gases produced in these burners, will be considerably hotter than ordinary pyrites burner gases, and will contain a larger quantity of SO_2 , in proportion to 100 the total gas volume, and a correspondingly smaller amount of free oxygen. Such a gas mixture may also be produced in any other suitable way if desired. By the use of this comparatively hot gas, the acid in the 105 Glover tower will be concentrated, more than in the ordinary operation of the chamber plant, and on account of the fact that

these gases are unusually high in SO_2 , the denitration will be more completely effected in the Glover tower, than in the ordinary manufacture of sulfuric acid, thereby effecting a considerable saving of nitrogen compounds.

The gases leaving the top of the Glover tower, as previously noted, will be somewhat deficient in free oxygen, on account of which

- 10 I introduce through the first atomizer 8, a certain quantity of free air, in order to furnish sufficient oxygen for the reactions to take place in the first chamber, along with said air, I introduce a spray of very fine
- 15 drops of acid, the result of which is an increased production of acid, in the first chamber, since each of these small droplets of acid, will form a nucleus, upon which sulfuric acid can readily condense. The carrying of the gases through the Lunge tower 12, will free the gases from all, or substantially all mist or fine drops of acid, after which the operation of again charging the gases in the system, with a fine mist of acid
- 20 will be repeated, in the gases, passing through the flue 7, leading into the second chamber. In each of the atomizers 8, I introduce a quantity of air, and the relative quantities of air introduced through the several atomizers in the system, will be regulated, in order to produce sufficient free oxygen for the reactions to take place in the following chamber and Lunge tower, with sufficient excess of free oxygen, to enable
- 25 the reaction to continue, at its maximum speed. The Lunge towers 12, may if desired, be cooled, by spraying the outside of these with water or other cooling fluid or they may be cooled in other appropriate ways, in order to remove the heat of reaction, and if so desired, the chambers 4, may likewise be sprayed with water or other cooling liquid, for the same purpose. In a modified form of procedure, I may use
- 30 acid from the last chamber, which may or may not be mixed with acid from the Gay Lussac tower, for feeding to all of the atomizers, and since the acid produced in the latter part of the system contains more
- 35 oxides of nitrogen, this will decrease the loss of niter from the system, and will also produce more acid in the respective chambers, by furnishing oxides of nitrogen to the gases.
- 40 55 Another advantage obtained by the use of these atomizers, is the thorough mixing of the gases, at a plurality of points in the chamber system. Instead of using chamber acid, in the several atomizers, I may employ
- 45 nitric acid, or waste nitrating acids, containing nitric and sulfuric acids, or other liquids containing nitric acid, or nitrogen-oxygen compounds. The atomizers 8, should, of course, be made of a material capable of
- 50 65 withstanding the corrosive effect of the

acids, and of the flue gases, glass being a suitable material, fused, silica also being suitable.

The atomizers should be of such construction, and operated in such a manner, that substantially the entire volume of gases passing through the flues 7, will be brought into contact with the spray of fine drops of acid.

If so desired, the flues 7, may also be constructed in such a manner, that the introduction of the air through the atomizers will act as an injector, to increase, and thereby regulate, the draft, or the passage of the gases through the system.

It will be noted from the drawing, that the mist of acid from the atomizers, is preferably introduced into the gases, in the same direction in which the gases are traveling through the system, which produces a more intimate mixture of the liquid particles with the gases, and also does not impede the flow of the gases through the system.

What I claim is:—

1. In the manufacture of acid in chambers, the step of repeatedly atomizing chamber acid into the chamber gases at a plurality of places by means of a gaseous fluid containing oxygen.

2. In the manufacture of sulfuric acid in chambers, the atomization in the direction of flow of the gases therethrough, of acid from those of the chambers where the acid contains a relatively large amount of nitrogen-oxygen compounds, into the gases in a plurality of the flues through which the gases enter the chambers.

3. In the manufacture of sulfuric acid in chambers, the step of atomizing into the gases traversing the flues of an acid-making system, and in the direction of flow of the gases therethrough, a mist of acid containing an oxygen-nitrogen compound, at each of a plurality of separate points.

4. In the manufacture of sulfuric acid in chambers, the step of mixing substantially the entire volume of the reacting gases, passing through a flue between two chambers, with an acid containing nitrogen-oxygen compounds, in the form of a mist of liquid particles, said mist being introduced in the direction of the flow of said gases, and introducing, at the same point, a gas containing an ingredient in which the chamber gases entering said flue are deficient.

5. The process of making sulfuric acid, which comprises the step of atomizing into at least one of the flues through which the gases enter the chambers, and in the direction of the flow of gases, chamber acid from the rear chambers.

6. The process of making sulfuric acid which comprises the steps of generating hot sulfurous gases containing less free oxygen than is necessary for complete conversion

into sulfuric acid by the chamber process, introducing in the direction of the flow of the gases a mist of fine particles of acid containing nitrogen-oxygen compounds and air at a plurality of separate points, separating at least a portion of said mist from the gases at each of a plurality of points, said air being in combined amounts, sufficient to produce an excess of free oxygen in the gases 10 in the rear part of the acid-making system.

7. The process of making sulfuric acid which comprises the steps of burning sulfurous material in air, in amount so restricted as to produce gases having insufficient free oxygen for complete commercial conversion into sulfuric acid by the chamber process, atomizing into the flues at a plurality of points, a mist of acid, containing a nitrogen-oxygen compound, by blast 15 of an oxygen-containing gas, and removing at least a part of the mist at each of a plurality of points, by passing the mist-laden gases through a space containing a filling material.

25 8. The process of making sulfuric acid which comprises the steps of burning sulfur-containing material in air in amount so restricted as to produce gases deficient in free oxygen, atomizing into the flues at a plurality of points, and in the direction of the 30 flow of the gases, and by means of blasts of air, mists of sulfuric acid of substantially chamber strength, said acid containing an oxygen-nitrogen compound, and removing 35 the mist from the gases at a plurality of points.

9. An apparatus for making sulfuric acid comprising a source of gases containing sulfur dioxide, a Glover tower, a series of 40 chambers, flues connecting these, atomizers arranged in at least some of said flues adapted to deliver a liquid into the gases, in the direction of flow of the gases and means for operating said atomizers.

45 10. An apparatus for making sulfuric acid comprising a burner for producing gases containing sulfur dioxide, means for regulating the composition of the gases produced therein, a Glover tower, a plurality 50 of chambers, flues connecting the burner, tower and chambers, and atomizers arranged to deliver a liquid into at least some of the

flues, in the direction of the flow of the gases therethrough, said atomizers being connected to the acid space in at least one of the 55 chamber bottoms, in combination with means for removing the mist from the gases at each of a plurality of points.

11. In the manufacture of sulfuric acid, the step of atomizing, in the direction of 60 flow of the gases therethrough, into at least some of the flues intermediate the chambers, sulfuric acid containing relatively more nitrogen-oxygen compounds than average chamber acid, said atomization being effected by a gas containing a constituent in which the chamber gases at the point of introduction are deficient.

12. In the manufacture of sulfuric acid by the "chamber process," the herein described steps of repeatedly atomizing, into the reacting gases, during the travel of the latter through the flues leading into at least some of the several chambers and in the direction of flow of the gases therethrough, a 75 mist of finely divided particles of an acid liquid containing nitrogen-oxygen compounds, passing the gases from at least a plurality of the chambers through spaces provided with fillings, whereby a major portion of the liquid particles is removed from such gases at such points.

13. Apparatus for making sulfuric acid comprising burners, a Glover tower, chambers, a Gay Lussac tower, and flues connecting such elements, atomizers arranged in at least some of said flues, delivering in the direction of flow of the gases therethrough, and gas and liquid connections to such atomizers.

14. An acid making system comprising burners, a Glover tower, chambers, a Gay Lussac tower, other intermediate filled towers, and flues connecting such elements; and atomizers in at least some of such flues, arranged to deliver in the direction of flow of the gases therethrough.

In testimony whereof I affix my signature in presence of two witnesses.
